PORTABLE CAR WASHING APPARATUS

Frank P. Walsh, St. Louis, Mo., assignor to Whiting Corporation, Harvey, Ill., a corporation of Illinois

Application December 3, 1942, Serial No. 467,688

7 Claims. (Cl. 15—53)

The invention relates to apparatus for washing railway cars.

One object of the invention is to provide a car washing apparatus which is portable and which can be easily and quickly transported for washing the sides of railway cars on any of a series of tracks in a yard or house where they are being serviced. By providing washing apparatus which is readily transportable into position to wash a railway car on any of a series of tracks the time and labor necessary to switch the cars onto a single track with which the washing apparatus is associated or the necessity of duplicating the apparatus for the series of tracks will be avoided.

Another object of the invention is to provide car washing apparatus of this type which can be wheeled into position for washing cars on any of a series of tracks and which is equipped with means for correctly spotting and securing the brushes in their correct position so that they will be pressed against the sides of the car respectively for effectively and simultaneously washing both sides of a car traveling past the brushes.

A still further object of the invention is to provide a simple and efficient portable washing apparatus comprising vertically extending power driven rotary brushes for washing the sides of railway cars.

Other objects of the invention will appear from the detailed description.

The invention consists in the several novel features which are hereinafter set forth and more particularly defined by claims at the conclusion hereof.

In the drawings:

Fig. 1 is a diagrammatic plan of apparatus embodying the invention and the equipment with which it is used, the motors for driving the brushes being omitted.

Fig. 2 is a side elevation of the washing apparatus partly in section, the spray shields being omitted.

Fig. 3 is a section taken on line 3—3 of Fig. 2.

Fig. 4 is a perspective of a portion of the supporting structure.

The invention is exemplified with apparatus which comprises two washing units of similar construction which are adapted to be located at the sides of a railway track for simultaneously washing the opposite sides of a railway car. Each unit comprises a vertically extending brush 10 of sufficient height to traverse and wash the entire side of the car and a shorter vertical brush 11 for washing the windows of the car.

Each brush 10 is fixed to a vertical drive shaft 12 and each brush 11 is fixed to a vertical drive shaft 13. The upper end of each of the drive shafts 12 and 13 is journaled in a bearing 16 which is carried by a horizontally swinging arm 17. The lower end of each shaft 12 is journaled in a bearing 14 which is carried by a horizontally swinging arm 15. The lower end of each shaft 13 is journaled in a bearing 18 which is carried by a horizontally swinging arm 22. The upper and lower arms for each brush are vertically aligned to permit the brushes to swing laterally. Each pair of arms 15 and 17 which carries a brush 10 is fixed to a shaft 20 which is journaled in a lower bearing 19 and an upper bearing 21. Each pair of arms 17 and 22 which carries a brush 11 is fixed to a vertical shaft 23, the upper end of which is journaled in a bearing 21 and the lower end of which is journaled in a bearing 24. Each pair of arms and the connecting shaft between them constitute a horizontally swinging support for one of the rotary brushes so that they will be normally positioned in the path of the railway car and will be deflected thereby as said car travels past the brush in either direction. Bearings 21 of each unit are fixed to the opposite end portions of a bar 27. Each bearing 19 is fixed to one end of a supporting plate 28. Each bearing 24 is secured to a supporting plate 29. A vertical electric motor 30 is supported on each of the arms 17 coaxially with its supporting shaft. A pulley 31 is fixed to the upper end of each of the shafts 12 and 13 and is driven by belts 32 from a belt pulley 33 on the lower end of the motor shafts.

The carrying arms for each of the brushes are normally held to extend inwardly at substantially right angles to the edge sides of the car and are movable in opposite directions from their normal position so that the brushes can be deflected in the direction of travel of the car and will remain in engagement with the car. Each of the brushes is normally and yieldingly held so it can be thus deflected in either direction by a device which comprises a sheave 38 which is fixed to the shaft which supports the arms which carries the brush, a cable 39 looped around and centrally fixed to sheave 38 with branches which extend backwardly around guide sheaves 30 and thence downwardly through openings 42 which extend through counter weights 43, respectively, and have fixed thereto a small weight 44 which is adapted to engage and lift and can be lowered away from one of the counterweights. Each weight 43 is guided in a cylinder 46 which

is fixedly supported on a bracket 48^a. When the supporting arms for the brushes are in centralized position both weights will be vertically supported and upon deflection of a brush by the railway car, one end of the cable 39 will lift one of the weights 43 while the other end of the cable will be paid out and held taut by the small weight thereon without lifting the other weight 43. The weights 43 when lifted, cause the brush to which they are connected to be pressed against the car. This exemplifies vertically extending power driven rotary brushes adapted to be positioned at each side of the railway car and means for supporting the brushes to permit them to be deflected in the direction in which the railway car is moving and for keeping the brushes engaged with the sides of the car for washing. A spray pipe 45 extends vertically between and is carried by each pair of brush-carrying arms for discharging jets of water onto each brush 10 while it is being driven. A flexible pipe section 46 supplies water to each spray pipe 45 from a supply pipe 47. Vertical pipes 48 are adapted to jet streams of water on the side of the railway car before and after it passes the brushes. Spray shields 49 are supported at the outer sides of the brushes to prevent splash from the brushes from being projected outwardly.

The supporting structure for the washing units comprises a frame at each side, the frames being spaced apart to support the washing units in operative relation to the sides of the railway car and to permit the cars to pass between them, and an overhead cross connection between the frames under which the railway car is adapted to travel. Each side-frame comprises a pair of spaced channel-beams 62 and a mast formed of a channel-beam 66 which are rigidly secured together. The lower end of beam 66 fits between a pair of channel-beams 62. Brace-beams 67 rigidly connect the outer ends of beams 62 to the flanges of the beam 66. The lower end of the beam 66 is additionally secured to beams 62 by angle plates 68. Brackets 63 are fixed under and to the outer ends of the beams 62 and each of said brackets carries an axle 64 for a flanged carrying wheel 65. Each bar 27 which carries the upper bracket for pivotally supporting the brushes 10 and 11, plates 28 and 29 which support the bearings for the shafts which carry the supporting arms for the brushes and bars 46^a which support cylinders 46¹ are welded to the inner faces of the beam 66. The overhead cross connection between the masts 66 comprises a pair of channel-girders 70 and plates 71 between the inner faces of the beams 70 and the side flanges of the beam 66. The mast 66, plates 71 and beams 70 are securely welded together to form a rigid overhead cross connection between the side frames so that the lower ends of the side frames will be fixedly supported in properly spaced relation and so that a cross connection between the lower portions of the frames can be dispensed with.

The equipment used with the washing apparatus comprises a pair of rails 73 which form a track for the wheels 65 which intersects the rails 74 of a series of railway tracks in a yard or house in which the cars are washed. The wheels 65 which carry the supporting structure for the washing units are adapted to run on the rails 73 at substantially right angles to the rails 74 of the tracks on which the railway cars travel, so that the supporting structure for the brushes will straddle any of the tracks for the railway

cars. The rails 74 are notched as at 75 to receive the flanges on the wheel 65 and permit the wheels to be rolled into position for washing railway cars on any of the tracks. The tracks 73 are laid in a walk 76 which extends across the tracks.

While the apparatus is washing a railway car the side frames should be equidistantly spaced from the side of the railway car being washed 10 and locked to cause the brushes of the units on opposite sides to be yieldingly pressed with uniform pressure against the sides of the car. During the operation of the washing units the supporting structure is subjected to considerable vibration. In order to spot the side frames transversely relatively to the cars being washed and to secure them in their spotted position, devices are provided at each side of the supporting structure for locking the side frames against lateral movement in the direction of and transversely to the travel of the railway cars. Each of these devices comprises a hand-lever 78 which is fulcrumed at 79 on the outer side of a mast 66, a pair of bolts or rods 80 which are slidably mounted 15 in the flanges of an outside beam 62, a pair of plates 81 countersunk in the walk 76 and provided with sockets for receiving the lower ends of rods 80, a bell crank lever 82 connected to the upper end of each of the rods 80 and pivoted to 20 the top of said cross beam 62, and links 83 between levers 82 and the hand-lever 78. While the supporting structure for the washer is being shifted for work from one track to another, the rods 80 will be held raised to clear the walk 76, 25 and when the supporting structure has been spotted to its correct position for washing the cars on one of the tracks formed by rails 74, the levers 78 at both sides of the structure can be shifted to lower the rods 80 into the socket plates 81 30 and to lock said structure.

Water is supplied to the supply pipes 48, 47 by means of a hose-connection which permits the washing apparatus to operate while the supporting structure is positioned for washing the cars on any of the tracks. Current is supplied to the 45 electric motors 30 by a power cable of sufficient length to make it possible for the machine to serve a railway car on several of the tracks.

The operation of the improved washing apparatus is as follows: The supporting structure is wheeled into position for washing the cars on any of the car tracks before the train of cars to be washed extends across the walk 76 and is locked in its spotted position by shifting the 50 levers 78 at both sides of the supporting structure to lock the rods 80 into the sockets in plates 81. The washing units will then be positioned so that a train of railway cars can travel between the power driven rotary brushes and both sides of the car will be simultaneously washed as they travel past the brushes. When the railway cars of another train on a different track are to be washed the levers 78 will be shifted to release the supporting structure and the latter will be 55 wheeled to another track and again locked into position in readiness for washing the cars in a train on said other track.

The invention exemplifies car washing apparatus which is adapted to simultaneously wash 70 both sides of a railway car and comprises a portable supporting structure and washing equipment whereby the washer can be readily and quickly shifted for use in washing cars on any of a series of usually parallel tracks so that it is not necessary to provide a washing apparatus for

the cars on each of the railway tracks and so that the work of washing trains of cars on different tracks can be expedited by a single apparatus.

The invention is not to be understood as restricted to the details set forth since these may be modified within the scope of the appended claims without departing from the spirit and scope of the invention.

Having thus described the invention, what I claim as new and desire to secure by Letters Patent is:

1. The combination with a pair of units for simultaneously washing the sides of a railway car traveling on a track, comprising vertically extending rotary brushes yieldingly supported for engaging the sides of the car and electric motors for driving said brushes, of a portable supporting structure for said units comprising side frames between which the car can travel, a rigid overhead connection between the side frames and under which the cars are adapted to pass, and carrying wheels adjacent the ends of the side frames whereby the structure can be wheeled across the track for operatively supporting the units for washing cars on different tracks, and means for releasably and positively locking the structure to the floor on which the track is laid and in operative positions for washing cars on the tracks.

2. The combination with a pair of units for simultaneously washing the sides of a railway car traveling on a track, comprising vertically extending rotary brushes yieldingly supported for engaging the sides of the car, and electric motors for driving said brushes, of a portable supporting structure for said units comprising side frames between which the car can travel, a rigid overhead girder-connection between the side frames and under which the cars are adapted to pass, and carrying wheels adjacent the ends of the side frames, a cross-track on which said wheels can travel for operatively supporting the units for washing cars on different tracks, and means for releasably and positively locking the structure to the floor on which the tracks are laid for securing the units for washing cars on different tracks.

3. The combination with a pair of units for simultaneously washing the sides of a railway car traveling on a track, comprising vertically extending rotary brushes yieldingly supported for engaging the sides of the car, and electric motors for driving said brushes, of a portable supporting structure for said units comprising side frames between which the car can travel, a rigid overhead girder-connection between the side frames and under which the cars are adapted to pass, and carrying wheels adjacent the ends of the side frames, a cross track on which said wheels can travel for operatively supporting the units for washing cars on different tracks, and devices on each side frame for releasably and positively securing the structure against lateral movement in spotted positions relatively to cars on said different tracks.

4. The combination with a pair of units for simultaneously washing the sides of a railway car traveling on a track, comprising vertically extending rotary brushes yieldingly supported for engaging the sides of the car and electric motors for driving the brushes, of a portable structure for supporting said units, comprising side frames between which the car can travel,

each frame including a pair of side-beams spaced apart, masts formed of a channel beam having its lower end extending between and fixed to the pairs of side-beams, a pair of channel-girders rigidly connecting the upper ends of the masts and under which the cars are adapted to pass, and carrying wheels at the ends of the side-beams adapted to travel crosswise of the track on which the cars travel, and devices mounted on the side frames for releasably locking the structure to operatively support the units for washing cars on different tracks.

5. The combination with a pair of units for simultaneously washing the sides of a railway car traveling on a track, comprising vertically extending rotary brushes yieldingly supported for engaging the sides of the car and electric motors for driving the brushes, of a portable structure for supporting said units, comprising side frames between which the car can travel, each frame including a pair of side-beams spaced apart, masts formed of a channel beam having its lower end extending between and fixed to the pairs of side-beams, a pair of channel-girders rigidly connecting the upper ends of the masts and under which the cars are adapted to pass, and carrying wheels at the ends of the side-beams adapted to travel crosswise of the track on which the cars travel, and devices comprising bolts, and levers for shifting the bolts, mounted on the side-frames, and stationary bolt receiving socket-plates stationarily secured in position to spot the structure relatively to the track on which the cars are washed.

35 6. Equipment for washing vehicles on a plurality of substantially parallel tracks, comprising: a pair of portable side frames spaced apart for travel between them of a vehicle on one of the tracks; vertically extending brushes for engaging the sides of the vehicle, yieldably supported on the side frames, respectively; electric motors for driving said brushes carried by the side frames, respectively; carrying wheels adjacent the ends of each side frame and journaled thereon for supporting them for rolling movement transversely of the tracks; and a rigid overhead connection between the upper ends of the frames and connecting them for conjoint transportation of the frames, brushes and motors from an operative position for washing a vehicle on one track to a position for washing a vehicle on another track disposed laterally thereof.

7. Equipment for washing vehicle on a plurality of substantially parallel tracks, comprising: a pair of portable side frames spaced apart for travel between them on a vehicle on one of the tracks; vertically extending brushes for engaging the sides of the vehicle, yieldably supported on the side frames, respectively; electric motors for driving said brushes carried by the side frames, respectively; a transverse intersecting track, carrying wheels adjacent the ends of each side frame and journaled thereon for supporting them on the intersecting track; and a rigid overhead connection between the upper ends of the frames and connecting them for transportation on the intersecting track of the frames with the brushes and motors thereon, from an operative position for washing a vehicle on one track to a position for washing a vehicle on another track disposed laterally thereof.
